M. A. CHERTOK,
RECEIVING HOPPER FOR METAL SCRAPS AND FILINGS.
APPLICATION FILED DEC. 8, 1916.

1,275,847.

Patented Aug. 13, 1918.

UNITED STATES PATENT OFFICE.

MOSES A. CHERTOK, OF ROXBURY, MASSACHUSETTS.

RECEIVING-HOPPER FOR METAL SCRAPS AND FILINGS.

1,275,847.

Specification of Letters Patent. Patented Aug. 13, 1918.

Application filed December 8, 1916. Serial No. 135,805.

To all whom it may concern:

Be it known that I, MOSES A. CHERTOK, a citizen of the United States, residing at Roxbury, in the county of Suffolk and State of Massachusetts, have invented a new and useful Receiving-Hopper for Metal Scraps and Filings, of which the following is a specification.

This invention relates to receiving hoppers used in connection with working tools or apparatus of the rotary type, as for example, grinding, polishing or drilling tools or apparatus, for retaining the scrap metals, filings or dust falling off from the object being worked on; thus providing a simple device which is adapted to surround the working member of said tools or apparatus and may be constructed in whole or in part of transparent material, as celluloid or glass, to allow an unobstructed view to the operator of the working member of the tool or apparatus housed therein. Therefore, in the working of precious metals, the hopper collects the metal filings or dust yielding therefrom and retains the same so that it may be reclaimed by the operator, thus naturally resulting in a saving instead of a waste, as is otherwise the case without the use of said hopper.

To illustrate my invention I have shown in the drawing one of its many embodiments wherein it is applied to the hand-piece of a dental engine which is used more particularly by dentists for grinding or polishing crowns, bridges, pivots, etc., all of which are made of the more precious metals and yield considerable filings or scraps in the working thereof.

Referring to the accompanying sheet of drawing—

Figure 1 represents a diagrammatic view, showing in section a transparent receiving hopper associated with an ordinary dental hand-piece and the hands of the operator indicated as holding a crown in working relationship with the grinding member of the hand-piece and in the process of being ground to size.

Fig. 2 represents a view taken on line 2—2 in Fig. 1 looking in the direction of the arrows.

Fig. 3 represents a sectional view taken on line 3—3, Fig. 1, looking in the direction of the arrows.

Fig. 4 represents an end view taken on line 4—4, Fig. 1, looking in the direction of the arrows, showing the engaging slot of the

stem of the hopper which disengagingly interlocks the hopper with the projecting stud of the hand-piece. 60

Fig. 5 represents a sectional view taken on line 5—5 in Fig. 4 looking in the direction of the arrows, and representing a modified type of hopper stem which is made integral with the hopper itself, instead of separate as shown in Fig. 1. 65

Fig. 6 represents an elevational view showing the device supplied with a flexible cot in the thumb opening of the hopper.

Fig. 7 represents a modified type of hopper in that the same consists of a rigid frame-member for the hopper which is supplied with a transparent shield for opening the view of the interior of the hopper to the operator. 70

The terms employed herein are used in the generic and descriptive sense and therefore are not intended primarily as terms of limitation.

Like numerals refer to like parts throughout the several views of the drawing. 80

The numeral 10 in its entirety represents a receiving hopper which is preferably made of transparent material, such as transparent celluloid, glass or the like, and is provided with the side or work-opening 11, through which the work, as the crown 12, may be inserted and brought into working engagement with the working member, as for example, the grinding wheel 13 of the hand-piece 14 found commonly employed with so-called dental engines. The hopper 10 may be provided with the integral type of stem 15, Fig. 5, or the separate type 16, Fig. 1, which, in either case, is provided with the hole 17 adapted to fit the hand-piece 14, as shown in Fig. 1, and may be made tapered, if necessary, to fit a tapering type of hand-piece. 90

The separate type of stem 16 may be made of metal, rubber, or any other suitable material, according as may be desired, and may be in some instances made flexible or resilient, if found advantageous, for gripping purposes or the like. The outer end thereof is preferably provided with the flange 18 which projects to form a ridge for the finger of the operator to engage with, and the length of the stem may be made to accommodate one finger, as for example, the first finger of the hand shown in Fig. 1, or may be extended beyond to accommodate more than one finger, if desired. 100

It will be found that a great majority of

the dental hand-pieces are constructed with a projecting-stud 19 (Fig. 1), which in connection with my device may serve as a retaining member for the same, and therefore 5 the stem of the same is preferably provided with the longitudinal-slot 20 and the annular-slot 21 which are made of a width sufficient to permit the engagement of the hopper-stem with said projecting-stud 19.

10 For use in the dental field, where a great deal of work is done by the operator with the hand-piece of the dental engine as shown in Fig. 1, the hopper 10 is preferably provided with the thumb-opening 22 which allows 15 for the insertion of the thumb of the hand holding the hand-piece, as shown in Figs. 1 and 2 for permitting the thumb to help support the work in working relationship with the working-end of the hand-piece, 20 and for applying the necessary pressure on to the work against the working-wheel 13 of the hand-piece 14.

In Fig. 6 the thumb-opening 22 is shown provided with a flexible cot 23 which completely 25 covers the opening 22 by a suitable overlapping end 24, which end may be permanently secured by any suitable means to the hopper. The cot 23 may be made flexible, as of rubber or fabric if desired, or of any 30 other such suitable material, to permit the thumb to manipulate within the hopper,—the purpose of the cot being used to completely close the opening 22 in the hopper so that no opportunity is given for the metal 35 particles to pass out through said opening around the thumb when inserted therein, as when a large opening is used in a smaller dimensioned hopper, which reaches into the through section of the hopper.

40 In Fig. 3, 25 represents a flexible washer made of rubber, or any other such suitable material, which may be permanently secured to the thumb opening of the hopper in any suitable manner and through which the thumb 45 may be inserted into the hopper, and thus provides for a complete inclosure around the thumb which will positively prevent the particles within the hopper from escaping therethrough while the tool is in action.

50 In Fig. 7, 26 represents a rigid frame-member which is preferably supplied with the integral type of stem 27 and may be provided with the thumb opening 28, to which 55 frame-member is secured the annular shield 29 which is preferably transparent and may be made of celluloid or glass, according as may be desired, and is held secured with said frame-member 26 by a suitable rigid ring-member 30 which is bolted as by 31, or otherwise suitably secured with the frame-member 26 for properly supporting said shield member 29 therewith,—it being here noted that said outer ring-member may be made

integral with said frame-member 26 and will 65 therefore require supporting sections or arms which will take the place of the bolts 31 (Fig. 7), and therefore will permit of the use of sectional transparent windows or plates to be inserted between the arms of the 70 frame instead of the annular shield member 29 shown in said Fig. 7.

Having thus described the parts of my invention as applied to a dental hand-piece which illustrates but one of the embodiments 75 thereof and without being limited thereto, the manner in which the same may be employed therewith is as follows:—

The hopper is positioned on the hand-piece 14 and may be preferably freely fitted 80 thereupon to allow an annular movement thereof, as may be required by the manipulation of the thumb within the same; and for that reason the annular-slot 21 is provided in the stem of the hopper so that such motion may be allowed where the projecting-stud 19 is found on the hand-piece 14. With the hopper thus set with the hand-piece 14 in working relation therewith, the operator is thus enabled to take hold of the hand-piece with the holding-hand A and preferably allows part of the hand to engage with the stem of the hopper, as shown in Fig. 1. The thumb T is then inserted through the opening 22 and is brought in range with the work, as the crown 12 shown in Figs. 1 and 2, which is held by the fingers F and T' of the other hand B, which enter within the hopper through the opening 11 and support the work in relation to the working-member 100 of the hand-piece in exactly the same manner as would ordinarily be the case if the hopper were not there, and so it will be observed that with the transparent hopper the operator possesses a full view of the work 105 and the operation being performed thereupon, and is not restricted by the hopper in his manipulation of the work or the working-member therein; also that the function of the hopper is to catch and hold within it 110 the particles of metal-scaps and filings yielding from the grinding, drilling or polishing process applied to the more precious metals, which particles ordinarily are otherwise lost and wasted, and therefore by 115 providing a suitable troughlike chamber within the hopper, the same will accommodate any reasonable amount of such particles within it which can be readily reclaimed by the operator and thus results in a great 120 saving of precious metal which is otherwise lost and wasted.

It may also be observed that the device is simple in construction and cheap to manufacture, and may be readily attached or detached from the hand-piece and does not at all interfere with the working operation thereof when attached thereto. Also, the

hopper may be permanently or detachably secured to a lathe or any other apparatus used in a laboratory or shop, for serving the same purpose, namely, to collect particles or scraps worked off from the object by the tool or instrument with which the hopper is associated for reclaiming purposes,—the same being especially useful in the manufacture of jewelry as well as in the dental art referred to.

While the preferred embodiments of my invention have been described in detail, it will be understood that I do not wish to be limited to the particular construction set forth, since various changes in the form, material, proportions, and arrangement of parts, and in the details of construction may be resorted to without departing from the spirit and scope of the invention, or destroying any of the advantages contained in the same, heretofore described and defined in the subjoined claims.

What I claim is:—

1. In a receiving hopper of the character described, a transparent hood-member surrounding the working tool on all sides pro-

vided with a retaining trough; and means for engaging the same with the working element associated therewith.

2. In a receiving hopper of the character described, an annular transparent hopper member forming a troughlike compartment therein, provided with an opening for the insertion of the work within the hopper; and an auxiliary opening for the insertion of the operator's finger in the hopper; and means for engaging said hopper member with the instrument or apparatus with which the same is to be associated.

3. In a receiving hopper of the character described, an annular transparent hopper member forming a troughlike compartment therein, provided with a main opening for the insertion of the work within the hopper and an auxiliary opening for the insertion of the operator's finger therein; a yielding washer member adapted to be secured about said auxiliary opening; and means for engaging said hopper member with the instrument or apparatus with which the same is to be associated.

MOSES A. CHERTOK.
